UNITED STATES PATENT OFFICE.

HARRY T. O'BRIEN, OF CHICAGO, ILLINOIS, ASSIGNOR, BY DIRECT AND MESNE ASSIGNMENTS, OF ONE-HALF TO FRANCIS R. SCHANCK, OF CHICAGO, ILLINOIS.

VACUUM CLEANER.

Application filed October 8, 1921. Serial No. 506,256.

My invention relates to vacuum cleaners and has for one of its objects the provision of a simple and efficient vacuum cleaning apparatus which can be operated by hand power or by motor power.

A further object is the provision of a nozzle with a brush therein and a brush housing dividing the nozzle into two inlet slots providing smooth air passages, or of two nozzles between which is mounted a brush or other means of loosening dirt from the object being cleaned, the brush not being in the path of the air will not obstruct its free access and therefore the smooth passages will permit greater velocity of the air and greater cleaning power with an equal amount of energy than where the passage-way is obstructed by a brush.

A further object is the provision of inlet slots, the openings of which lie in such planes that the normal axes of the entering air currents will be substantially parallel to the direction of the path of the particles of dirt loosened by the brush, and will therefore carry into and through the cleaner heavier particles and hence more thoroughly clean than if the air current were in some other direction with relation to the path of the dust particles moved by the brush.

A further object is the provision of air inlet slots on opposite sides of the dirt loosening device so that the air currents will catch up dirt equally well when the sweeper is moved backwardly or forwardly.

A further object is the provision of inlet slots so related to the brush that the air currents are away from the brush tending to keep it clean and not towards it or through it which would tend to draw dirt and threads into the brush.

A further object is the provision of air passages without abrupt changes of direction or cross-sectional area, but with air passages of properly designed curves and smooth interior without obstructions in the air passage from the inlet slots, through the nozzle, fan chamber, fan, and into the dust catching bag. I have found that abrupt changes in direction or considerable changes in cross-sectional area of air passages or the presence of irregular obstructions cause eddies and changes in velocity of the air currents which prevent the air currents

from transporting the maximum amount of material which the average air velocity induced by the same suction means would otherwise transport.

A further object is the provision of air passages of such internal cross-sectional area as to cause air velocity of substantially uniform transporting power, taking into account whether the air currents are traveling vertically, horizontally, or in some other direction in order to obtain maximum cleaning efficiency.

A further object is the provision of a vacuum cleaning device having both motor power and hand power operation with provision for operating either of the powers at will.

A further object is the provision of an electrically or hand driven vacuum cleaner so arranged that the electrical circuit cannot be completed except when the mechanical connection between the motor and the suction device is in operating condition to prevent possible danger of starting the motor when only the hand operating device is connected to the suction fan.

While I have shown the application of a brush between two nozzles or inlet slots, this same principle could readily be applied to three or more inlet slots with a brush lying between each pair of slots, or it may be applied to a cleaner originally designed with only a single wide slot with a brush inserted therein. In the latter case a properly formed covering or housing may be placed over the brush leaving it exposed on its lower face, but the housing dividing the original nozzle into two nozzles with smooth walls and proper cross-sectional areas and causing higher velocities of air currents than if the brush were as originally placed as an obstruction in the air passages, thereby increasing the cleaning power of the sweeper.

Other objects will appear hereinafter. An embodiment of the invention is illustrated in the accompanying drawings, forming a part of this specification, and in which—

Fig. 1 is a fragmental plan view of a vacuum cleaner embodying my invention, the same having parts broken away to show underlying portions;

Fig. 2 is an end elevation of the same with parts broken away to show underlying portions;

Fig. 3 is a rear view of the same with parts broken away to show underlying portions;

Fig. 4 is an enlarged fragmental section taken on line 4—4 of Fig. 1;

Fig. 5 is a section taken on line 5—5 of Fig. 4;

Fig. 6 is a fragmental section taken on line 6—6 of Fig. 1;

Fig. 7 is an enlarged section of a driving clutch on line 7—7 of Fig. 3;

Fig. 8 is a fragmental plan view of a hand or electrically driven vacuum cleaner embodying my invention with parts broken away to show underlying portions; and

Fig. 9 is a side elevation of the device of Fig. 8 with parts broken away.

Referring more particularly to the drawings, I have indicated a housing 11, which in the present instance is formed so as to contain a centrifugal fan 12 for producing suction. This fan 12 preferably has curved vanes 13 which are attached to plates 14 and 15, and has a concave cone-shaped center 16 to deflect the air current from its axial to its radial path with little loss of velocity. The plate 15 has an opening 17 at its center for taking in air. The air is discharged at the periphery of the fan between plates 14 and 15 and passes out through discharge opening 18 at the rear of the housing 11. A separator bag 19 is connected to the opening 18, and said bag may be of any approved design.

Extending from the bottom of the fan 12 is a housing 21 enclosing a passage 20 which terminates at its front end in a nozzle with inlet slots 22 and 23. The passage 20 is preferably formed so that its effectual cross-sectional area is substantially the same throughout its length and is equivalent to the areas of inlet slots 22 and 23 and to the rest of the air passage up to the bag, taking in account the difference in the wall friction and considering the variation of the direction of the air currents with respect to the direction of gravity as affecting the transporting power of air.

The slots 22 and 23 are defined by the lower edges or lips 24 and 25 of housing 21 and the lower edges or lips 26 and 27 of a brush housing 28 disposed in said nozzle. The ends of brush housing 28 are preferably open, as indicated in Figs. 1 and 9, and ears 29 and 30 attached to the housing 21 for supporting the journals 31 and 32 of a rotary brush 33 in the housing 28. The journal 31 at one end of the brush 33 is mounted in a bearing 34 in ear 29, (see Fig. 9), and the other journal 32 of said brush is mounted in an irregular groove 35 in the ear 30, (see Fig. 6). This arrange-

ment permits the brush to be easily removed.

In removing the brush, one end is pressed over against the side of the housing 28 compressing part of the brush and this permits the journal 32 to move out of the irregularly shaped groove 35 and the brush to move out of the housing. When the first-mentioned end of the brush is out of the housing, the other journal will slip longitudinally out of the circular bearing 34 to free the brush. In placing the brush back in position again, the reverse order is had.

Intermediate the ends of the brush 33, and in the present instance it is indicated at the center, is a pinion 36 which meshes with an internal gear 37 formed in an annular wheel 38. The walls of brush housing 28 are enlarged as at 39 so as to accommodate the wheel 38. The enlargement is preferably slightly larger than the wheel so as to permit the free rotation of the wheel and extends down over the periphery of the wheel sufficiently far to hold it in operative relation to the pinion 36 and also in position in the nozzle.

I preferably arrange the lip 26 higher than lip 24 of slot 22, and lip 27 higher than lip 25 of slot 23, so that the lips of said slots adjacent the brush 33 will be so related to the other lips of said slots that the planes of the openings or inlet slots 22 and 23 are approximately normal to the path of the particles of dirt loosened by the brush in operation, causing the currents of air entering said slots to be substantially parallel to the path of the particles of dirt from the brush. This particular disposition of the planes of the inlet slots 22 and 23 also causes the entering air currents to be away from the brush instead of toward it, tending to keep the brush clean. These features greatly increase the efficiency or cleaning power of the machine.

It will be apparent that the housing walls 28 of the inlet slots may be integral with the other walls of the nozzle 21. It should be understood, however, that when desired the housing 28 may be made detachable so as to be applicable to a cleaner having a wide nozzle with a brush in the wide nozzle air path. In such event the application of housing 28 to such wide nozzle, together with the brush, results in the arrangement shown in the drawings, including the inlet slots, as described herein. This arrangement may also be adapted to three or more inlet slots placed so that the brushes or dirt loosening devices may be placed between each two adjacent inlet slots with substantially the same effect.

In the housing 11 is a vertical shaft 40 upon which the centrifugal fan 12 is fixed. The shaft is journaled in suitable bearings 130

is said housing and is provided with a worm 41 adjacent its lower end. The worm 41 meshes with a worm wheel 42 which is secured to a hub 43. The hub 43 and worm wheel 42 are loosely mounted on a hardened collar 44 and the latter fixed on a shaft 45 which is mounted in the casing. The ends of the shaft 45 engage the traction wheels 46.

10 The hub 43 has one or more openings 47 therein in each of which is mounted a ball 48 adapted to engage the collar 44 to effect rotation of the member 43 with the shaft when the device is moved in one direction. When the device is moved in the other direction the balls 40 roll back in the openings 47 against the influence of the springs 49, permitting the traction wheels to turn without driving the suction fan. 15 With this arrangement it will be apparent that when the device is moved backwardly the ground wheels will turn, but not rotate the fan. Since the fan will be rotated at a relatively high speed it will continue to move during the backward pulling of the device.

20 At the top of the casing 11 I provide an opening 50 in which is secured a plate 51 by any desired securing means. The shaft 30 40 preferably has a non-round socket or depression 52 in its top end which is adapted to receive a motor driven connection so that the device can be driven by a motor when desired.

35 The device may be sold with the plate 51, as indicated in Fig. 2, so that such device will be used only by hand power, and when it is desired to add a motor later the plate 51 is removed and a plate 53 put in its place.

40 The plate 53 carries a motor 54 which may be of any approved construction. The shaft 55 of the motor is indicated as having a beveled gear 56 splined thereon and the latter meshing with the gear 57 fixed on a shaft which has a portion 58 engaging the socket 52 so that when the gears 56 and 57 are in mesh the motor can operate the shaft 40 and fan 12. The gear 56 has a groove 59 in its hub which is engaged by an irregularly shaped member 60 and the latter has a hand portion 61 which extends out through a slot 62 in a housing 63 on plate 53. By means of the part 61 the gear 56 can be moved back and forth on shaft 55 to connect and disconnect the motor with the fan.

45 I preferably provide a separable plug, which may be of the ordinary construction, in the electrical circuit of the motor and mount one part 64 of such plug rigidly on the plate 53. The removable part 65 is preferably in the path of member 61 so that when member 65 is removed from member 64, member 61 can be moved in its slot 62 to disconnect gear 56 from gear 57. The

arrangement also is such that member 65 cannot be connected with member 64 when the gears are disconnected. With this arrangement it is impossible for one to start up the motor when the gears are disconnected. If the gear 56 were moved into engagement with gear 57 when the motor was running, parts of the device might be injured.

50 In this construction the motor is arranged to drive the fan at a higher rate of speed than the traction wheels 46 do so that said wheels need not be disconnected from the fan at any time. When the device is being motor operated, the shaft would turn at so high a rate of speed that one could not readily push the device along fast enough to make the balls 48 engage the collar 44. However, no damage would result if these did engage due to rapid movement of the sweeper along the floor. When the device is to be hand-operated, the member 61 is moved to disconnect the gear 56 so that it is not necessary to turn the motor shaft when operating the device by hand. Any suitable handle may be attached to the casing for moving the device along, and such a handle connection is indicated at 64 in the drawings.

55 I claim:

1. Cleaning apparatus comprising a nozzle, a suction producing means, a housing containing a passage connecting said nozzle and said suction producing means, an electric motor, a connection between the electric motor and the suction producing means, an electric circuit including the motor, and means for preventing completion of electric circuit when the electric motor is not operatively connected with suction means.

2. Cleaning apparatus comprising a casing, a suction means in said casing, a motor having a shaft mounted in the casing, an electrical circuit including the motor, means for operatively engaging and disengaging said motor shaft with said suction means, said engaging and disengaging means being adapted when in one position to prevent completion of the electric circuit.

3. Cleaning apparatus comprising a housing having an opening in one side, a suction fan mounted in the housing adjacent said opening, a shaft extending through said suction fan and having a recess non-round in cross-section in one end thereof, a plate secured in the opening of said housing, an electric motor mounted on said plate, and a driving connection having means detachably engaging the non-round recess of said shaft and said electric motor providing a detachable connection between the shaft and motor.

4. Cleaning apparatus comprising a casing; pumping means mounted in said casing; an electric motor attached to the casing; a driving connection between the mo-

- tor and pumping means; a separable electrical plug attached to the casing and connected with said electric motor; and a member attached to said driving connection and adapted for movement adjacent one portion of said separable plug prohibiting the connection of the other part of said plug when the driving connection is inoperative condition.
- 10 5. Cleaning apparatus comprising a casing; suction pumping means in said casing; a motor shaft mounted in the casing; a gear connection between the pumping means and motor shaft; and a member ~~for ditcon-~~ connecting said gear connection, said member 15 having a portion adapted to move along a fixed path; and an electrical connection having two separable parts, said member having its path of movement adjacent one of the parts of said electrical connection and 20 adapted for movement adjacent the latter so as to prohibit the connection of the two parts of said electrical connection.
- In testimony whereof I have signed my name to this specification on this 6th day 25 of October, A. D. 1921.

HARRY T. O'BRIEN.
